UNITED STATES PATENT OFFICE

JOHN M. HOTHERSALL, OF BROOKLYN, NEW YORK, ASSIGNOR TO AMERICAN CAN COMPANY, OF NEW YORK, N. Y., A CORPORATION OF NEW JERSEY

APPARATUS FOR PUNCHING SHAPES FROM SHEET METAL

Application filed December 27, 1926. Serial No. 157,204.

This invention relates to an apparatus for cutting blanks from sheet material, and while it has more particular reference to the manufacture of can ends from strips 5 having undulating edges of the stagger layout, it will be readily manifest that the invention has other and valuable application.

It has been customary in connection with the operation of cutting and forming presses 10 in the manufacture of circular articles, such as can ends, to provide an automatic feed which moves a previously prepared strip of tin plate or the like past a cutting station in such timed step by step action as to insure 15 the removal of one of the circular articles from each adjacent space of the strip. The strip is previously prepared to provide the most economical cutting operation. A removal from the strip of the greatest area of 20 metal and which leaves the smallest possible skeleton scrap, of course, effects greatest economy and largest production from the sheet material. This is accomplished when the sheet of metal is divided into strips in 25 accordance with what is known as the "stagger layout". This "stagger layout" permits the outer edges of the circles of one row to lie closely to the outer edges of the circles of adjacent row. This type of layout is ob- 30 tained by forming strips with scroll or undulating edges, the edges of adjacent strips dovetailing or interlocking with each other when arranged side by side. In dividing a sheet of tin plate into strips of this char- 35 acter, it is, of course, apparent that cer- tain of the strips will have portions of their ends too small to provide the primary circular objects for which the strip is laid out. These end portions, under the present 40 method, are removed from the end or ends of the strips and are subsequently fed to what is known as a recovery press in order to get smaller articles therefrom as, for example, can ends of narrow or oblong type. 45 This operation of removing the end pieces in the shearing machine which forms the strips and the subsequent somewhat difficult operation of feeding the removed end pieces into a press for the purpose of re- 50 covery does, of course, entail considerable

expense, occasioned by the handling and feeding of the pieces and the operation of the recovery press itself.

My present invention contemplates the removal of the recovery pieces in the press 55 cutting out the larger can ends for which the layout is or was originally designed and this without interfering with the usual action of the press or reducing its speed and capacity. 60

My invention contemplates the removal of the recovery piece from the advance end of the strip simultaneously with removal of the first full size can end or primary article and where the following or rear end of 65 the strip provides a recovery to cut this from the material by a normal operation of the press.

A further object of the invention is the attainment of the recovery through the em- 70 ployment of automatic presses of standard construction and through the mere addition of recovery dies and the provision of an additional supplemental feeding device which can be readily incorporated in the 75 press without appreciable alteration and change.

Numerous other objects and advantages of the invention will be apparent as it is better understood from the following de- 80 scription, which, taken in connection with the accompanying drawings, discloses a preferred embodiment thereof.

Referring to the drawings,

Figure 1 is a partial front elevation of an 85 automatic strip feed press;

Fig. 2 is a partial end elevation thereof;

Fig. 3 is a view showing the "stagger lay- 90 out" and before the strips are sheared from the sheet; and

Figs. 4, 5, and 6 are diagrammatic views 95 illustrating the recovery action.

For the purpose of illustrating my pres- 95 ent invention, I have shown on the draw- ings a strip feed press comprising, the usual base 11 and upright or arbor 12. The arbor 12 carries guides 13 in which a slide or die support 14 is reciprocated by the pitman 15 from the crank-shaft 54 carrying fly- 100 wheel 55. The usual side extension 22 sup-

ported from bracket 23 is provided and contains the reciprocating feed bar 24 on which are mounted the spring pressed dogs 25. The strip from which the articles are to be cut is fed into a slot formed by guide members 21 in the usual manner.

Reference character 26 indicates the usual male cutting die for cutting out the can end and this is held in place in the slide 14 by the holding plate 16. It will, of course, be understood that the die 26 is adapted to co-operate with a companion die 17 arranged in the bed 18, which in turn is supported on the base 11. So much of the strip feed press as has been thus far described is of standard construction and detail showing and description is thought unnecessary.

I mount a recovery die 27 adjacent the die 26 and for conjoint movement therewith, and it will be noted that this die 27 is of smaller size than the die 26 and is adapted to cut a recovery or secondary article or blank from the strip operating and from portions that heretofore have constituted the recovery pieces earlier described.

Referring now to Fig. 3, reference character 33 indicates the scroll strips produced by the staggered cut-out. The lines of cut for the primary articles or round can ends are indicated by dotted lines 33'. It will be noted that this stagger layout provides end portions 20' and 20'' of the strip 20 which are inadequate in area to provide full size round can ends. The dotted lines indicated by reference character 20^a illustrate the shape and size of the intended recovery from the strips shown on the drawing.

Fig. 4 discloses the relation of the two dies 26 and 27, and when the strip is fed laterally into the slot or guideway 19 with the portion defined by the line 20^a under the recovery die, the first operation of the press will cut or punch from the sheet a primary round can end and a secondary or recovery oblong blank. Thereafter the feed slide 24 advances the strip to the position shown in Fig. 5, from which it will be noted that the recovery die passes idly through the opening just previously formed by the main or primary die 26, this die at this time cutting a second full sized can end from the next complete full width portion of the scroll strip. The strip is progressively fed on through the press until the main die has completed its operation upon the last full size portion of the strip, at which time the strip passes out of engagement with the main feeding mechanism and comes under the control of a second feeding device which will now be described and which gives it a longer feed than that of the step by step feed movement required for the successive operations of the main die 26. This action may be observed by comparing Figures 4 to 6, wherein the normal feed of the appara-

tus is indicated by the dotted line B—A, this being the distance between centers of successive circular lines of cut. In order that the main die may not spoil the end of the strip of which recovery is to be made, the feed of the strip must carry its end out of the zone of action of the main die and into the path of the secondary or recovery die 27. This length of feed is indicated on the line C—A in Fig. 6.

An extension 36 is provided on the delivery end of the strip feed press and a feed slide 34 is arranged to reciprocate in guideways 35 in this extension. A link 39 is pivoted to this feed slide 34 at 38 and this link 39 in turn is pivoted at 40 to one arm 41 of a bell crank lever. This bell crank lever is pivoted at 42 in an upward extending arm 43 on the extension 36. A link 45 is pivoted to the other arm 44 of this bell crank lever and also at 47 to an arm 46 of a second bell crank lever mounted upon the arbor or upright 12 earlier described. The upright 12 carries a shaft 53 geared to the shaft 54 in any suitable manner. A cam 52 is mounted on the shaft 53 and is engaged by a roller 51 upon the second arm 50 of the bell crank pivoted at 48, the other arm 46 of which is, as has been explained, connected at 47 with the link 45. The shaft 53 makes one complete revolution (clockwise, Fig. 2) to complete a cycle of operations for one strip. In other words, the shaft 53 is synchronized with the shaft 54 to permit a given number of strokes of the dies 26 and 27, during which time a complete cycle of movement, as effected by the cam 52, takes place to provide for the final feeding of the strip. The feed slide 34 is provided with feed dogs 37 which frictionally engage upon the top of the strip and the travel of the feed slide is such as to impart to the strip the travel C—A shown in Fig. 6, this travel being accomplished by passage of the cam roller 51 along a steep portion of the cam 52, as shown in Fig. 2. Outer movement of the feed dogs 37 takes place during the raising of the die support 14 and as the cam roller reaches the position shown in Fig. 2, there is a momentary pause in the travel of the feed dogs to permit the final cutting action by the recovery die 27 from the end 20'' of the strip. As the die carrier 14 moves upwardly, further continued rotation of the cam 52 by reason of the contour of its cam groove further moves the feed dogs 37 outwardly in the same direction and ejects the skeleton strip from the machine.

Consideration of the contour of the groove of the cam 52 will show that when the roller 51 is nearest the shaft 53 the feed dogs 37 are in their innermost position, as illustrated in Fig. 1 and as the cam moves in a clockwise direction, as viewed in Fig. 2, the steep

part of the cam moves the roller 51 further from the shaft 53 bringing it into the position illustrated in this figure. As previously described, this brings the strip into position for the final recovery cutting operation as shown in Fig. 6. Further rotation of the cam then moves the feed dogs 37 still further outwardly for the ejecting operation, as previously described. Further movement of the feed dog, as controlled by oscillation of the bell crank 46 on its pivot 48 then returns the feed dogs at a relatively slow rate and throughout half of the rotation of the cam 52 and thence further returns the feed dogs at a more rapid rate of travel as the cam roller is moved towards its innermost position closest to the shaft 53. It will be understood that while the feed dogs 37 are being returned, as just described, the several cutting operations are taking place, the strip being advanced at such time by the initial feeding mechanism comprising the feed dogs 25. The springs of the feed dogs permit the strip to be moved thereunder, the strip at such time moving toward the right (Fig. 1) while the feed dogs are moving in the opposite direction.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

- 40 1. In an apparatus for cutting objects from strip material, the combination of, a reciprocating primary cutter for cutting full size objects from said strip, a strip feeding device successively presenting portions of the strip to said cutter, a secondary or recovery cutter mounted adjacent and conjointly movable with the primary cutter and of a size adapting it to pass through the openings formed previously by the primary cutter, and means presenting to said secondary cutter a portion of the strip inadequate in area to receive a full cut of the primary cutter.
- 55 2. In an apparatus for cutting articles from strip material, the combination of, a primary cutter adapted to cut articles of a maximum size permitted by the strip, means presenting successive portions of the strip to said cutter, a secondary or recovery cutter mounted adjacent and movable with said primary cutter and of a size adapted to pass through openings previously formed in the strip by the primary cutter, and a second feeding device operable after the primary cutter has finished its operations on the strip

to arrange a waste or recovery portion of the strip for operation by the secondary or recovery cutter.

3. In an apparatus for cutting articles from strip material, the combination of, a primary cutter and a secondary cutter arranged side by side and adapted for simultaneous operation upon said strip to cut a recovery piece from an end thereof and an article of maximum size permitted by dimensions of the strip, and means progressively thereafter feeding the strip past said cutters and arranging uncut portions of the strip in the path of the primary cutter and cut portions of the strip in the path of the secondary cutter.

4. In a strip feed apparatus, the combination of, conjointly movable primary and secondary cutters, means feeding a scroll strip past said cutters and presenting full width portions successively to the primary cutter, and second feeding means presenting a waste or recovery portion at the end of the strip to the secondary cutter.
